MAGNETIC HOLDER FOR DISPLAY CARDS

Macy O. Teeter, New Castle, Ind.

Application December 29, 1945, Serial No. 638,106

3 Claims. (Cl. 40—10)

1

This invention relates to a holding device for display cards and the like and more particularly to a holding device that is adapted to retain display cards or the like in a vertical or slightly angular display position by magnetic means.

Heretofore, there have been employed various means or structures for holding display cards and the like in vertical position which either were more or less makeshift in character or of an elaborate nature. Those of the makeshift type comprised unsightly wood blocks, heavy weights, or other miscellaneous objects not specifically designed for such purposes and wholly unsuited for window display purposes. The display card holders of the more elaborate type, however, comprised relatively large ornamental frames and structures, and while such elaborate holders performed their intended function with some degree of satisfaction, their size, specialized structural natures and expense nevertheless rendered them commercially undesirable.

It is, therefore, an object of the present invention to provide an improved holding device for display cards and the like that is adapted to support such articles in proper display position by magnetic means.

Another object of the invention is to provide an improved supporting means for display cards and the like that is relatively small in size, of inexpensive and simplified construction and at the same time has substantially universal application to display cards of all shapes, sizes and dimensions.

A further object is to provide a holder for display cards and the like by which such articles may be readily placed in approximately vertical display position and supported therein against inadvertent displacement.

Other and further objects and advantages will become apparent as the description progresses, reference being had to the accompanying drawing, in which:

Fig. 1 is a side elevational view of a card holding device comprising a preferred embodiment of the present invention and illustrated in operable card supporting position;

Fig. 2 is a bottom plan view of one of the magnetic holding units comprising an element of the improved card holding device; and

Fig. 3 is a front elevational view of the card and a magnetic holding unit as viewed from the right in Fig. 1.

Generally, the display card holding device illustrated in the accompanying drawing comprises a pair of magnetic supporting units 10 and 11

2

that are carried on a flat metal plate 12 and between which a card 13 may be supported in proper vertical position for display purposes. The flat metal plate 12 which may be composed of a metal having a high magnetic attraction, has a thin felt pad 14 secured on its under side to prevent injury to any surface upon which the improved display card holder may be placed. The metal plate 12 is rectangular in shape and is of sufficient breadth and width to prevent any rocking or tilting movement in any direction which might result under the influence of large or top-heavy cards or as a result of an inadvertent striking of the card.

15 The holding units 10 and 11 may be of identical construction and each comprises a solid one quarter sphere or body portion 16 composed of plastic or other suitable material into which has been molded a permanent U magnet 17. As shown 20 more particularly in Figs. 1 and 2 of the drawing, the magnet 17 is disposed crosswise of the one quarter sphere 16 in spaced and substantially parallel relationship to the vertical face thereof and its north and south pole faces project to and are flush with the bottom surface thereof where they are exposed for intimate engagement with the upper surface of the metal plate 12. The bottom surface of each one quarter sphere 16 is flat from edge to edge and together with the flat exposed 25 pole faces of each magnet 17 present flat bearing surfaces which permit a wide overall bearing contact between the holding units 10 and 11 and the flat surface of the metal plate 12, and hence a close intimate engagement between the pole faces of the magnet 17 and the plate 12 to insure the maximum degree of magnetic attraction.

Secured to the vertical faces of each one quarter sphere 16 by cement or other suitable means is a thin flat plate 18 which also may be composed of plastic or other suitable material. The lower edge of each plate 18 is flush with the lower surface of each one quarter sphere 16 so as to facilitate the intimate bearing contact between the units 10 and 11 and the flat plate 12. As shown in Fig. 1, the vertical faces of the one quarter spheres 16 are disposed at right angles to the metal plate 12 so that the plastic plates 18, when secured to those faces, will also assume vertical positions at right angles to the metal plate 12. As a result, the outer faces of the plastic plates 18, when placed in opposed relation as shown in Fig. 1, are parallel with respect to each other from top to bottom and from side to side so as to be equidistant at all points and capable of firmly holding a card 13 in intimate engagement

therebetween without the formation of any angular space which would tend to permit rocking or tilting of the card 13. Should the vertical face of one of the one quarter spheres 16 be disposed out of the perpendicular with respect to the plate 12, the vertical face of the other one quarter sphere may be formed at a complementary angle so that when the plastic plates 18 are secured thereto, their opposed vertical faces, while each is disposed out of the perpendicular, nevertheless are parallel to each other and capable of holding the card 13 firmly therebetween as above described.

The plastic plates 18 are substantially rectangular in shape and are of sufficient height and width to be considerably larger in area than the vertical faces of the one quarter spheres 16 and to present a larger bearing surface for supporting engagement with the display card 13.

When it is desired to mount a card 13 in a store window, for instance, for display purposes, the metal plate 12 may first be placed in proper position on the horizontal surface of the display area. Then, the magnetic holding unit 10 may be placed with its bottom surface in engagement with the metal plate 12 at a point centrally located with respect to the side edges thereof but slightly to the rear of the transverse center line thereof. The supporting unit 10 will be retained thereafter in the foregoing position because of the magnetic attraction that is set up between the exposed pole faces of the magnet 17 and the metal plate 12, and it will resist thereafter any inadvertent application of moderate force tending toward displacement thereof. The display card 13 may then be placed in upright position with its lower edge resting on the plate 12 and with one of its sides against the vertical face of the plate 18 of the unit 10, after which the unit 11 may finally be brought against the card 13 with its lower surface also in intimate engagement with the plate 12 and moved into opposed relationship with respect to the unit 10 so that the card 13 is firmly held in proper vertical position between the two plastic plates 18. In this final assembled position shown in Fig. 1, the units 10 and 11 are definitely and securely held by magnetic attraction down in position on the plate 12 against inadvertent horizontal and vertical movement and serve to maintain the card 13 in proper display position at all times against the natural tendency of the card 13 to tip forwardly or backwardly.

It is apparent that the improved card holding device described above not only serves to properly hold a display card in proper upright position at all times, but also possesses other inherent advantages. The one quarter spheres 16 with the magnets 17 molded therein and their plastic plates 18 may be readily and inexpensively produced in a wide variety of attractive colors and assembled together with a minimum of labor requirements. Also, while the units 10 and 11 possess relatively great holding power through the attraction of their magnets 17 for the metal plate 12, they nevertheless are light in weight, as is the thin metal plate 12, so as to permit effortless handling thereof as contrasted with lead, glass or other types of weights that have heretofore been employed. Ease of handling also arises from the fact that units 10 and 11 are capable of retaining themselves on the metal plate 12 during transportation thereof, thus eliminating the difficulty of carrying a group of disassembled elements and the danger of loss or separation of the elements

4
during periods of non-use. It is also apparent that the metal plate 12 serves as a keeper for the magnet 17 at all times during periods of use and non-use so as to greatly lengthen the efficient operable life of the magnetic units 10 and 11.

Further, the card holding spheres, because of their magnetic attraction for the metal plate, are capable of effectively clamping in upright display position cards of any thickness or any number of cards, such as an entire card file which may be temporarily removed from a card drawer or file.

Although there has been shown in the drawing and described above one preferred embodiment of my invention, it will be apparent that variations and modifications may be made without departing from the underlying principles of the invention. For instance, it is apparent that a rigid vertical plate permanently secured to the metal plate 12, or some other abutting member, could be substituted for the magnetic unit 10, so that the card 13 could be held in vertical position between such a plate or member and the magnetic unit 11. It is intended, therefore, by the following claims to include within the scope of the invention all variations and modifications by which the results of the invention may be obtained through the use of substantially the same or equivalent means.

I claim:

30. 1. A holding device for supporting a display card or the like in substantially vertical position comprising a flat magnetic metal plate and a plurality of supporting units adapted to be carried by and retained in position on the surface of said plate by magnetic attraction and to maintain a card or the like in substantially vertical position therebetween, each of said units comprising a body portion having a flat substantially vertical face and a substantially flat bottom face for engagement with said plate, a magnet at the bottom of said body portion having its magnetic poles spaced apart in exposed flush relationship with the bottom face of said body portion and adapted to magnetically attract said metal plate, and a flat upright bearing plate fixed to said vertical face of said body portion and extending outwardly to a substantial extent from said body portion whereby to provide an enlarged bearing area for engaging and supporting a card or the like.

2. A holding device for supporting a display card or the like in upright position comprising a flat magnetic metal plate and a plurality of supporting units adapted to be carried by and retained in position on the surface of said plate by magnetic attraction and to support a card or the like therebetween, each of said units comprising a body portion having a magnet at its lower portion with its magnetic poles spaced apart in a plane parallel with said metal plate and adapted to magnetically attract said metal plate, and a flat upright bearing member secured to said body portion and adapted to bear against a card or the like for support thereof, said bearing member being of substantially greater extent than said body portion whereby to provide an enlarged bearing area for intimately contacting and firmly retaining a card or the like.

3. A holding device for supporting a display card or the like in substantially vertical position comprising a flat magnetic metal plate and a plurality of supporting units adapted to be car-

ried by and retained in position on the surface of said plate by magnetic attraction and to maintain a card or the like in substantially vertical position therebetween, each of said units comprising a body portion having a flat substantially vertical face and a substantially flat bottom face for engagement with said metal plate, a magnet at the bottom of said body portion having its magnetic poles spaced apart in exposed flush relationship with said bottom face, and a flat surfaced outwardly extending bearing plate secured to the vertical face of said body portion for bearing engagement against a card or the like for support thereof, said bearing plate having substantially greater lateral dimensions than said vertical face of said body portion whereby to provide an enlarged bearing area for engaging and supporting a card or the

like and said plate having its bottom edge in substantially flush alignment with said bottom face of said body portion.
